United States Patent Office

Des. 212,880
Patented Dec. 10, 1968

212,880

PORTABLE SEAT

Ricardo Victorero, 6406 W. Flagler St.,
Miami, Fla. 33144

Filed Jan. 18, 1967, Ser. No. 5,475

Term of patent 14 years

(Cl. D15—8)

FIG. 1

FIG. 2

FIG. 3

FIG. 4

FIG. 7

FIG. 6

FIG. 5

FIGURE 1 is a perspective view of a first embodiment of my design showing the front, top, and left side of a portable seat;

FIGURE 2 is a rear view of said first embodiment;

FIGURE 3 is a bottom view of said first embodiment;

FIGURE 4 is a perspective view of another embodiment of my design showing the front, top, and left side of the portable seat;

FIGURE 5 is a rear view of said other embodiment;

FIGURE 6 is a bottom view of said other embodiment; and

FIGURE 7 is a right side view of said other embodiment.

I claim:

The ornamental design for a portable seat, as shown.
